PRINTING TELEGRAPH APPARATUS

Carl A. Levin, Chicago, Ill., assignor to Teletype Corporation, Chicago, Ill., a corporation of Delaware

Application April 25, 1938, Serial No. 204,038

9 Claims. (Cl. 178—27)

This invention relates to printing telegraph apparatus and particularly to printing telegraph apparatus in which the characters are printed in page form from type elements carried upon the periphery of a rotatable and selectively arrestable type wheel.

An object of the invention resides in the provision, in a printing telegraph receiving unit embodying a type wheel having displaceable type elements, of instrumentalities for actuating said elements capable of extremely rapid positive operation.

Another object of the invention resides in the provision, in a keyboard controlled signalling mechanism, of instrumentalities for causing a mechanical function to accompany the operation of certain signalling keyboard members.

Another object of the invention resides in the provision of a simplified, easily assembled type wheel of the kind having displaceable type elements.

The invention features apparatus for actuating the individual type elements of a type wheel including a print hammer which is actuated by a cam follower and having a yieldable element included in the linkage interposed between the print cam and the print hammer whereby the actual printing operation is performed by the expenditure of kinetic energy of the print hammer and possibly an additional element or elements, such kinetic energy resulting in overtravel of the print hammer permitted by the yieldable element.

The invention also features a keyboard mechanism in which a mechanical condition that is set up in a printing telegraph receiving unit as the result of the generation of a particular signal combination either locally or distantly is abolished by a mechanical action resulting from the operation of the key lever which, upon being operated, causes the generation of a signal combination which, while being entirely unrelated to the signal combination which established the mechanical condition, is particularly suited to be in process of generation at the time of abolition of mechanical condition.

In a copending application Serial No. 77,796, filed May 4, 1936, by Albert H. Reiber, there is disclosed a type wheel printer with reference to which the present invention stands as an improvement. According to the disclosure of that application the displaceable type elements carried by the type wheel are individually actuated by a pivoted actuating member which is operated by a pivotally mounted impact member or

hammer. Operation of the hammer through a full stroke sufficient to cause the printing of a character is effected by a cam operated bail.

According to the present invention a reciprocable printing member is provided for actuating the type elements individually. A bail carries a follower roller which engages the periphery of a printing cam, the bail being biased into engagement with the cam by a tension spring. Operation of the printing member is effected when the printing bail cam follower roller rides down an abrupt drop in the printing cam. The distance through which the printing bail is operated by its spring is insufficient to bring the printing member into engagement with a type element. A spring is interposed between the printing bail and the printing member, and inertia of the element to which motion is imparted by the printing bail causes those elements to overtravel, the interposed spring yielding and permitting the overtravel, and the amount of overtravel is sufficient to cause a selected type element to effect printing. The spring which yields and permits the overtravel immediately retracts the printing element to unoperated position, thereby clearing the path of unoperated type elements so that the type wheel may be rotated to a new position.

A type wheel disclosed in copending application Serial No. 77,796 and also in a copending application Serial No. 77,794, filed May 4, 1936, by Howard L. Krum et al., comprises spaced slotted flanges joined by a cylindrical drum portion which is also slotted. Type pallets slidable radially of the type wheel are mounted in the slots in the type wheel, there being two type pallets in each slot. The shanks of the type pallet in the upper row have recesses which open downwardly, and the shanks of the type pallets in the lower row have recesses which open upwardly. A garter spring individual to each row of type pallets is disposed in the recesses in the shanks of all of the type pallets in a row and biases the pallets to their innermost positions. A floating ring partially enters the space between the two garter springs, whereby it rests upon and is supported by one of the springs and whereby it also prevents the springs from shifting out of the desired position.

In the type wheel according to the present invention the drum portion of the wheel which joins the upper and lower flanges has a peripheral rib intermediate the upper and lower flanges. The rib thus divides the surface of the drum portion into two peripheral grooves which serve as seats for the garter spring and confine the

springs in the desired position. The garter springs are thus kept in proper position without the assistance of a floating ring.

The copending application Serial No. 77,796 disclosed signal responsive function mechanism for closing a pair of contacts which establish a short circuit across the transmitting contacts of the keyboard transmitter mechanism so that the telegraph line to which the transmitter and receiving unit are connected will not be affected should any of the signal transmitting key levers be operated, the purpose of the contacts being to disable the transmitter and to place the apparatus in a receiving only condition. The function lever which closes the contacts becomes latched to hold the contacts closed. The present invention contemplates the provision of a contact unlatching attachment for the key lever of the keyboard transmitter mechanism which initiates a letters or unshift signal combination. Thus, when the unshift key lever is operated, the permutation code mechanism is set for the transmission of the unshift signal combination, the transmitting distributor is released for operation, and the latch which is holding the short circuit across the transmitting contacts is disabled so that the short circuit is broken. The unshift or letters key lever is peculiarly adapted to perform the unlatching of the short circuiting contact for the reason that the letters or unshift signal combination, according to a generally used permutation code system, is the all-marking combination, in which all of the code impulses are of marking nature. Thus, the short circuiting contacts may be permitted to open at any time during the cycle of rotation of the transmitting cam shaft without the line actually becoming opened, the transmitting contacts maintaining the line in closed condition. Since the transmitting contacts impose a continuous marking condition upon the line during the rotation of the transmitting cams, the opening of the short circuiting contacts cannot introduce a spacing condition and therefore the receiving distributors of receiving units connected to the line will not be released for an idle or unwanted receiving operation.

Certain features of invention disclosed but not claimed herein are also disclosed and are claimed in copending applications Serial No. 193,642 filed March 3, 1938 by Albert H. Reiber, Serial No. 203,021, filed Apr. 20, 1938, by Bertheil F. Madsen, Serial No. 208,761, filed May 19, 1938, by Edward S. Larson, Serial No. 210,816, filed May 31, 1938, by Carl W. Swan, and Serial No. 211,496, filed June 3, 1938, by Herman Lotterman.

For a complete understanding of the invention, reference may be had to the following detailed description to be interpreted in the light of the accompanying drawings, wherein

Fig. 1 is a perspective view of the combined transmitting and receiving mechanism according to the present invention, certain portions being broken away to clarify the showing;

Fig. 2 is a plan view with portions broken away showing an alternative arrangement of apparatus for actuating the type pallets and a keyboard transmitter disabling function mechanism and latch;

Fig. 3 is a view partly in elevation and partly in section showing details of the type pallet operating mechanism and of the type wheel, the type pallet operating mechanism being shown in

elevation and the type wheel being shown in section; and

Fig. 4 is a vertical sectional view through a keyboard transmitter mechanism showing the transmitter shunt contact unlatching mechanism.

Referring now to the drawings and particularly to Fig. 1, the reference numerals 16 and 17 designate generally the typing unit and keyboard transmitter unit, respectively, of a printing telegraph apparatus embodying the present invention. The keyboard transmitter unit 17 is generally similar to the transmitter disclosed in copending application Serial No. 77,796, filed May 4, 1936 by Albert H. Reiber, and typing unit 16 embodies improvements on the typing unit disclosed in the copending application.

The foundation of the keyboard transmitter unit is the base casting 18 to the forward vertical wall of which is secured a slotted comb 19. A plurality of key levers 21 are pivoted within the casting 18 for rocking movement in a vertical plane, and these key levers protrude from the interior of base 18 through a slot in comb 19. The key levers 21 are provided with keytops 22 and are arranged to impart characteristic settings to permutation code bars contained within base 18 as fully disclosed in Patent No. 1,595,472 granted August 10, 1926 to Howard L. Krum. To the code bars are articulated lock levers 23 pivotally supported intermediate their ends and projecting above the upper surface of base casting 18 through apertures therein. The lock levers 23 are therefore subject to permutative setting by the code bars under the control of key levers 21.

The upwardly projecting portions of the lock levers 23 are disposed between brackets 24 and 26 secured to base 18, and aligned with each of the lock levers 23 is a contact controlling lever 27, the levers 27 being pivotally supported by a pivot rod (not shown) extending between brackets 24 and 26. A transmitting contact spring 28 individual to each of the levers 27 is mounted between insulating strips upon laterally extending portions of brackets 24 and 26, as indicated at 29. The upper end of each contact spring 28 engages a gooseneck portion of lever 27 and the flexing of contact spring 28 into and out of engagement with a shorter associated contact spring is controlled by gooseneck lever 27. The rocking of the gooseneck lever 27 is, in turn, controlled by the lock levers through blocking lugs (not shown), a lever 27 being unblocked when its corresponding lock lever is presented in extreme clockwise position and being blocked when its corresponding lock lever is in extreme counterclockwise position.

Bracket 24 and another bracket designated by the reference numeral 31 rotatably support a signal transmitting distributor shaft 32. Near one end shaft 32 has secured thereto a gear 33 to which rotation is continuously imparted by another gear as will presently appear. Adjacent to gear 33, shaft 32 has secured thereto the driving element 34 of a jaw clutch. A driven clutch element 36, slidable upon shaft 32, is keyed to a cam sleeve 37 and is urged toward clutch driving element 34 by a compression spring 38. A pivoted clutch throwout lever 39 normally holds driven clutch element 36 out of engagement with driving element 34 against the force exerted by compression spring 38. Clutch throwout lever 39 has an arm 41 which terminates substantially in engagement with an abutment screw 42 carried

by a clutch tripping bell crank 43. A depending arm 44 of bell crank 43 has its outer end disposed in the path of a lug 46 carried by a link 47 which enters the keyboard base 18 and is there connected to a universal bail (not shown). When link 47 is shifted forwardly of the keyboard transmitter base by operation of the universal bail under the control of one of the key levers 21, it rocks bell crank 43 clockwise which, in turn, trips clutch throwout lever 39 and permits spring 38 to shift driven clutch element 36 into engagement with driving element 34. As link 47 is moved forward, it is cammed downwardly by co-operation of a cam projection 48 with the head of a screw 49 carried by a forwardly extending portion of bracket 26. The camming of link 47 downwardly permits the free end of arm 44 of bell crank 43 to escape from lug 46 so that bell crank 43 may return immediately to its extreme counterclockwise position and permit clutch throwout lever 39 to return immediately into position for arresting the clutch comprising elements 34 and 36 at the conclusion of one revolution thereof, even though a key lever should be held depressed and link 47 retained in its forward position for a prolonged interval of time. Thus the operation of cam sleeve 37 by the jaw clutch is confined to single revolution in response to each operation of a key lever. A tension spring 51 maintains engagement between cam projection 48 of link 47 and the head of screw 49.

The cam sleeve 37 carries a lock bail operating cam 52 and a plurality of impulse timing cams 53. Cam 52 controls the operation of a lock bail 54 pivotally supported by brackets 24 and 26, lowering the bail into blocking relation to the lock levers 23 as the cam sleeve 37 begins to rotate, and lifting it at the end of a cycle. The function of the lock bail 54 is to prevent the shifting of lock levers 23 during a cycle of rotation of the impulse timing cams 53 and thus preventing mutilation of a signal combination established by the depression of a key lever 21. Each of the cams 53 is aligned with one of the transmitting contact control levers 27 and is engaged by a portion of the aligned lever. Each of the cams 53 has a notch 56 in the periphery thereof which, when presented to the associated transmitting contact control lever 27, releases that lever for rocking movement in counterclockwise direction, and the lever 27 rocks unless restrained by its associated lock lever 23. The recesses 56 in the several cams 53 are arranged spirally about the cam assembly so that the levers 27 are released for rocking movement successively. When a lever 27 is permitted to rock counterclockwise by its cam 33, its contact spring 27 flexes into engagement with the associated short contact spring and a current impulse is impressed upon the telegraph line, the duration of which corresponds to the interval in which the lever 27 remains in its counterclockwise position. The cams 53 thus distribute to the telegraph line the signal impulses corresponding to a character represented by a key lever depressed. One of the contact controlling levers 27 has no lock lever associated with it and operates invariably once in each cycle of operation of the transmitting cam for impressing on the line the stop impulse.

The principal foundation element of the typing or receiving unit is a casting which mounts on the keyboard base 18 and has a portion 61 located centrally of the base 18 and a portion 62 extending transversely of the base 18 in proximity to the rear edge thereof. Thumb screws are employed

for securing the casting comprising portions 61 and 62 to the base 18, one of those screws being indicated at 63. A secondary casting 64 extends transversely of the keyboard base 18 and is secured to portion 62 of the primary casting by any desired means, such as screws. The primary casting supports all of the power driven shafts, the operating cam assemblies, the selector mechanism, the printing mechanism, and the ribbon feed mechanism. The secondary casting 64 supports the platen carriage and associated mechanism, the signal bells, and a set of levers by which various functions are performed.

The primary selector mechanism which integrates the signal combinations generated in the keyboard transmitter mechanism, hereinbefore described, or in a remote transmitter, is indicated generally by the reference numeral 66 and is generally similar to the primary selector mechanism disclosed in the hereinbefore identified co-pending application of Albert H. Reiber, Serial No. 77,796. The principal elements of the selector mechanism 66 are a selector cam assembly 67, a selector magnet 68, and a sword and T-lever assembly 69, the last mentioned assembly as well as the selector magnet being supported by a mounting plate 71 carried by the forwardly extending portion 61 of the primary casting. The selector cam assembly 67 is carried by the upper end of a vertically positioned shaft which is rotatably supported in bearing blocks 72 and 73. The selector cam assembly 67 has flanges 74 secured thereto at opposite ends, and in spaced relation to each flange 74 is a flange 76 secured to the shaft which supports the cam assembly 67. A friction disc 77 occupies the space between each of the flanges 74 and the adjacent flange 76. Considerable friction is generated between the discs 77 and those positioned on either side of them so that selector cam assembly 67 will rotate with its supporting shaft except when restrained under the control of selector magnet 68, as is well known in this type of single magnet selector mechanism.

Just above the point at which it enters lower bearing block 72, the shaft has secured thereto a gear 78. An electric motor (not shown) drives a pinion which meshes with gear 78 so that the shaft to which the gear 78 is secured is continuously rotated. It may be added at this point that a gear 79 carried by a stub shaft meshes with gear 78 and that a spiral gear 81 also secured to the stub shaft meshes with gear 33 carried by the transmitter shaft 32. Thus rotation is imparted to the transmitting distributor shaft 32 from the motor pinion through gears 78, 79, 81, and 33.

The sword and T-lever mechanism 69 is actuated under the joint control of selector cam assembly 67 and the selector magnet 68 to interpret or integrate a series of impulses representing a signal combination preparatory to setting T-levers 82 in accordance with the signal combination. Each of the T-levers 82 engages one arm of a transfer bell crank 83, the other arm of which is articulated to one of the notched code discs 65 of a code disc selector mechanism indicated generally by the reference numeral 84.

The code disc selector mechanism 84 has a circular arrangement of vertically positioned stop pins 86 which project through slots in the top-most plate of the mechanism. Stop pins 86 are biased inwardly radially of the code disc selector mechanism and near their upper ends they rest against the edges of shiftable notched code discs as is fully disclosed in the copending application 75

of Albert H. Reiber, Serial No. 77,796. The notching of the code discs is such that for any permutative setting of the discs under the control of T-levers 82 one only of the stop pins 86 finds 5 presented to it an alignment of notches, whereupon the pin therefor enters the alignment of notches under the influence of its biasing spring, its upper end moving inwardly. A type wheel stop arm 87 clamped to type wheel shaft 88 is of 10 such length that in revolving, it just clears those of the stop pins 86 which are held in their outermost positions by the code discs, but finds blocking its path any pin 86 which has entered an 15 alignment of notches in the periphery of the code discs. The type wheel shaft 88 extends downwardly through the code disc selector mechanism 84 coaxially thereof and receives a continuous 20 torque from the driving motor through any convenient means, such as a gear carried by the shaft 88 and connected thereto by friction discs, the gear being continuously in mesh with the motor pinion. With this arrangement, the shaft 88 is always prepared to rotate and is free to do so when any stop pin 86 which had been previously 25 selected is moved out of the path of the stop arm 87 upon the resetting of the code discs. With this arrangement, shaft 88 may be arrested in any angular position in which stop arm 87 encounters a stop pin 86.

30 The setting of the T-levers 82 according to the operation of the sword lever mechanism 69 is controlled by a transfer bail 91 which is cam operated as will presently appear. Transfer bail 91 is pivotally supported by an upper mounting screw 92 and by a lower mounting screw which 35 does not appear in Fig. 1. Transfer bail 91 is biased in counterclockwise direction by tension spring 93 and has oppositely extending arms 94 and 96, the former of which is only partially indicated in Fig. 1 but which supports transfer 40 springs, as is clearly indicated in the copending application Serial No. 77,796, and the latter of which carries a locking blade 97 that cooperates with extensions 98 of T-levers 82. Locking blade 45 97 ordinarily blocks the extensions 98 of T-levers 82 whether they be presented in extreme clockwise or counterclockwise position. The rocking of transfer bail 91 in clockwise direction to effect the resetting of T-levers 82 is accompanied by 50 withdrawal of locking blade 97 out of the path of movement of T-lever extensions 98. When the transfer has been completed, transfer bail 91 returns to its extreme counterclockwise position and locking blade 97 is restored to locking position with respect to extensions 98.

55 The front portion 61 of the primary foundation casting for the typing unit has secured thereto spaced brackets 101 and 102. A shaft 103 is rotatably supported in vertical position between brackets 101 and 102. Shaft 103 has secured thereto near the lower end a gear 104 which permanently meshes with a gear 106 supported by gear 78 and secured thereto by any desired means, such as screws. The hub of gear 104 60 has secured thereto the driving portion 107 of a positive engagement clutch mechanism, the driven portion of which is indicated by the reference numeral 108. The driven element 108 may be of the type disclosed in copending application Serial No. 165,437, filed September 24, 1937, by B. F. Madsen, having in its periphery a groove designated 109 in the present application, which receives the portion 111 of the clutch throwout lever 112. The portion 111 of the clutch throwout 65 lever 112 confines driven clutch element 108

to substantially complete engagement with driving element 107 during a cycle of operation following the tripping of the clutch, and prevents acceleration of the driven element of the clutch from the speed imparted to it by the driving element 107, should any torque generated by negative load resulting from the interaction of a cam follower and its cam be applied to the driven clutch element 108. Driven clutch element 108 is slidably splined or keyed to a cam assembly 10 sleeve 113 and is urged into engagement with driving element 107 by compression spring 114.

5 Clutch throwout lever 112 is carried by the lower end of a pivoted bail 116, the upper pivot of which is indicated 117. At its upper end, bail 116 is provided with an arm 115, the free end of which is disposed in the path of the lowermost cam projection 120 of selector cam assembly 67. Bail 116 is biased in counterclockwise direction by tension spring 121. When cam projection 120 on selector cam assembly 67 encounters arm 115 of bail 116, the bail is rocked in clockwise direction, thus withdrawing clutch throwout lever 112 from restraining engagement with the driven clutch element 108 of the clutch on the front shaft, and permitting driven element 108 to move into engagement with driving element 107 whereby rotation is imparted to cam sleeve 113.

30 Cam sleeve 113 supports three cams designated 118, 119, and 125. Cam 119 is engaged by a follower roll 122 carried by an arm 123 secured to transfer bail 91. The direction of rotation of cam sleeve 113 is counterclockwise and cam 119, in being rotated, imparts clockwise rotation 35 to arm 123 and therefore to transfer bail 91. Transfer bail 91, as previously set forth, effects the permutational rearrangement of T-levers 82 and therefore the notched code discs in the code 40 disc selector mechanism 84 in accordance with a signal combination which has been integrated in the sword lever mechanism 69.

35 As previously set forth, there is a shaft rotatably supported in vertical position by bearing blocks 72 and 73 to which the gear 78 is secured. Below bearing block 73 the shaft has secured thereto the driving element 124 of a positive drive clutch, the driven element of which is indicated 45 129. Driven element 129 is slidably splined or keyed to a main cam assembly 130 and is urged 50 into engagement with driving element 124 by a compression spring 126. The engagement and disengagement of the elements 124 and 129 of the main cam assembly driving clutch mechanism is controlled by a pivoted clutch throwout 55 lever 127 to which is secured an arm 128 that extends forwardly of the typing unit and terminates in the path of the apex of cam 118 carried by cam sleeve 113 on the front shaft. As indicated in Fig. 1, in which the clutch mechanism on the shaft and on the main cam driving shaft are shown in their rest positions, the rest 60 position of the apex of cam 118 is a small angular distance in counterclockwise direction from the end of arm 128 which effects the tripping of the main cam clutch comprising elements 124 and 129. Since, as previously stated, cam cylinder 113 rotates in counterclockwise direction, it will be 65 apparent that cam 118 operates upon arm 128 to effect the tripping of driven clutch element 108 just before cam 118 reaches the end of a cycle of operation.

70 The bracket 101 which rotatably supports the upper end of shaft 103 pivotally supports a bail 131, the pivot being indicated 132. The bail 131 75

supports a cam follower arm which has been omitted from the showing of Fig. 1 for the reason that it would conceal substantial portions of the main cam assembly 130 carried by the rotatable shaft which is supported in bearing blocks 72 and 73. The cam follower arm carries at its free end a follower roll which engages cam 125 at a point between cam assemblies 113 and 124. The contour of cam 125 comprises a smooth gradual rise and a sharp drop-off, the drop-off being indicated by a reference numeral 133. As cam 125 rotates counterclockwise, it shifts its follower roll away from the axis of shaft 103 and thus imparts a counterclockwise rotation to bail 131. In the rest position of cam 125, the drop-off 133 is a small angular distance beyond the point of engagement of the cam follower roll with cam 125. The tendency of the cam 125 therefore is to permit bail 131 to return sharply to its extreme clockwise position just before cam 125 reaches its rest position. However, as will presently appear, a cam included in the cam assembly 130 assumes control of bail 131 just before the sharp drop-off 133 in cam 125 is presented to its follower, and the cam in cam assembly 130 holds bail 131 in extreme counterclockwise position for a predetermined interval and thereafter controls the restoration of bail 131 to its extreme clockwise position.

Bail 131 has integral therewith an arm 134 which extends toward the rear of the typing unit and terminates in a spring hanger hook 136. Hook 136 supports one end of a tension spring 137, the opposite end of which is connected to an arm 138 of a type wheel supporting frame 139.

Frame 139 is provided with a vertically disposed slot 141, through which extends a stud 142 supported by a portion of the frame of the typing unit. At the top, frame 139 has a horizontally extending portion 143 through which type wheel shaft 88 passes and in which is rotatably held the hub of a type wheel 144. Vertically disposed guide pins 146, only one of which appears in Fig. 1, are supported by a stationary bracket 147 at the top of the typing unit and pass through apertures in the horizontal portion 143 of type wheel supporting frame 139. The pins 146 and the cooperating elements comprising slot 141 and stud 142 permit oscillatory movement of frame 139 vertically, and guide the frame in that movement. Frame 139 is provided with an abutment screw 148 against which arm 134 of bail 131 rests when the bail 131 is in extreme clockwise position and frame 139 is in the lowermost position. When bail 131 is rocked in counterclockwise direction by cam 125, bail arm 134 tends to move out of engagement with abutment screw 148 and spring 137 tends to be distended. Spring 137, in turn, lifts frame 139, and thus type wheel 144, to the normal position of which is below the printing line, is elevated so as to bring character elements carried upon the periphery of the type wheel into position to effect printing in line upon a page carried in engagement with cylindrical platen 149. When bail 131 is restored to its extreme clockwise position, arm 134 engages abutment screw 148 and restores frame 139 to its lowermost position which, in turn, restores type wheel 144 to its lowermost position, whereby each character becomes visible immediately after being printed.

As previously set forth, main cam sleeve 130 is set in operation by the tripping of clutch throwout lever 127 by cam 118 included in front 75 cam assembly 113 just before cam 118 reaches

its rest position. The uppermost of the cams carried by cam assembly 130, designated 151, is engaged on the periphery thereof by a follower roll 152 carried at the end of a lever 153 which is pivoted at 154. Lever 153 has integral therewith an arm 156 which is provided near its outer end with a plurality of spring connection apertures 157. Any one of the apertures 157 is adapted to receive one end of a tension spring 158, the other end of which is supported by a spring post 159. Spring 158 biases lever 153 in counterclockwise direction, thus urging cam follower roll 152 into engagement with the periphery of cam 151. The several spring mounting apertures 157 in arm 156 of lever 153 are at different distances from spring post 159 so that the tension exerted by spring 158 and therefore the torque applied to lever 153 may be varied.

A print hammer operating bail 161 is pivotally supported by pivot 154 and coaxially mounted 20 pivot 162. At its lower end, bail 161 is provided with an arm 163 which supports adjustable abutment screw 164 and also one end of a tension spring 166. The inner end of abutment screw 164 25 engages an arm 167 of lever 153 and the rearmost end of tension spring 166 is also connected to arm 167 of lever 153. With this arrangement, bail 161 tends to occupy extreme clockwise position with respect to lever 153, the extremity of the position being determined by abutment screw 30 164.

Print hammer operating bail 161 has integral therewith at its upper end a lever arm 168. At its free end, lever arm 168 is loosely articulated to a print hammer 169. Print hammer 169 extends between ribbon spools 171, rotatably mounted upon a ribbon feed mechanism supporting plate 172. Print hammer 169 is provided with upper and lower arms 173 and 174, respectively, which are disposed in the same vertical 40 plane. Lower arm 174 enters a slot in a bracket 176, carried by ribbon feed mechanism foundation plate 172, and by means of slotted bracket 176, print hammer 169 is held in a vertical plane and is guided in reciprocatory motion imparted 45 by arm 168 of bail 161. The upper arm 173 of print hammer 169 is longer than the lower arm 174 and extends across the periphery of type wheel 144 and across the upper end of type wheel shaft 88. At its free end, arm 173 is provided 50 with a depending portion 177 which, in turn, is provided with an arm 178, the location of which is in alignment with the foremost portion of platen 149, which portion is at the level where printing occurs. Print hammer 169 is provided 55 in its lower edge with a shallow recess 170, the base of which rests upon and slides upon a retainer bar 175 secured to ribbon mechanism base plate 172. The motion of print hammer 169 to effect printing is limited by engagement of one 60 end of recess 170 with bar 175, and the restorative motion may, if desired, be limited by engagement of the other end of recess 170 with bar 175.

The print hammer 169 may be lifted out of 65 its position above the type wheel 144 to permit adjusting or changing the type wheel, by springing the free end of print bail arm upwardly until the rearmost end of recess 170 clears bar 175, whereupon arm 174 of the print hammer may be 70 drawn clear of slotted bracket 176, and the print hammer may be rotated upwardly in a vertical plane about its pivot of articulation with bail arm 168.

Type wheel 144 may be generally similar to 75

the type wheel disclosed in the hereinbefore identified application of Albert H. Reiber, Serial No. 77,796, and also in application Serial No. 77,794, filed May 4, 1936, by Howard L. Krum et al. As shown in those copending applications and as clearly indicated in Fig. 1 of the present application, type wheel 144 is provided with a plurality of radially disposed type pallets 179 which are reciprocably mounted in radial slots in type wheel 144, and are provided at their outer ends with type elements 181. There may be two superposed rows of type pallets 179, and by means of the lifting of type wheel supporting frame 139 by lever 134, either of the rows of type pallets 179 may be brought into alignment with rearwardly presented portion 178 of print hammer 169. For any angular position of arrestment of type wheel 144 by the cooperation of type wheel stop arm 87 with a selected stop pin 86, two of the type pallets 179 will be directed toward platen 149 in the same vertical plane as print hammer 169. According to the distance that type wheel 144 has been lifted by lever arm 134, the distance being controllable, as will appear later, one or the other of the type pallets 179 will be disposed directly in the path of portion 178 of print hammer 169.

Cam 151, in its normal or rest position, holds print bail operating lever 153 in extreme clockwise position in opposition to the tension of spring 158. Spring 166 holds print hammer bail 161 in extreme clockwise position with its abutment screw 164 in engagement with arm 167 of print bail operating lever 153. Thus, print hammer 169 is held in retracted position. At a predetermined time in the operation of cam 151, a sharp drop-off is presented to follower roll 152 of print bail operating lever 153. When the drop-off is encountered, lever 153 is rocked sharply in counterclockwise direction by spring 158. Lever 153 imparts counterclockwise movement to bail 161 through abutment screw 164. The angular distance through which lever 153 rocks, as cam follower 152 descends to the lowest or innermost point on the periphery of cam 151 is just short of sufficient to drive print hammer 169 positively against the type pallet 179 aligned therewith. However, the inertia of bail 161 and print hammer 169 causes spring 166 to yield and abutment screw 164 to move out of engagement with arm 167. Thus print hammer 169 overtravels or moves a greater distance than it would if positively interconnected with lever 153, the overtravel being caused by the inertia of bail 161 and print hammer 169, and being permitted by spring 166.

As soon as the energy generated by the inertia of bail 161 and print hammer 169 has been expended, spring 166 withdraws print hammer 169 in the direction of its retracted position until abutment screw 164 returns into engagement with arm 167 of lever 153. The remainder of the movement of print hammer 169 to its rest position is effected by the restoration of lever 153 to its extreme clockwise position by cam 151. The overtravel in the movement of print hammer 169 is sufficient to reciprocate the aligned type pallet 179 radially of type wheel 144 to effect printing. During the period of overtravel and restoration, the free end of arm 173 of print hammer 169 is presented between the type pallets adjacent to that which is being operated, so that the type wheel 144 could not be rotated, even if permitted to do so by arm 87, due to the fact that interference 75 between arm 173 of print hammer 169 and adja-

cent unoperated type pallet would occur. Spring 166 withdraws print hammer 169 from a position of interference with unoperated type pallets much more rapidly than it could be withdrawn if positively connected to print hammer bail operating lever 153. Thus, with the arrangement hereinbefore described, the print hammer 169 is projected and retracted in the shortest possible interval of time so that more time may be allowed for the rotation of type wheel 144 to the position 10 corresponding to the next selection.

In a preceding paragraph, the lifting of the type wheel to bring either of its two rows of type pallets into printing position was described. The lifting is accomplished by the counterclockwise 15 rocking of bail 131 which has an arm 134 interconnected with the type wheel supporting frame 139 by spring 137. It was stated that the lifting of the type wheel supporting frame 139 is effected by a cam 125 on the front shaft. It was also 20 stated that the lowering of type wheel supporting frame 139 is controlled by a cam included in the cam assembly 120 on the main shaft. This cam is indicated by the reference numeral 186, and is of the internal species having its cam surface 25 on the inside of a depending peripheral flange. The internal cam surface is engaged by a follower roller carried at the free end of an arm 187, secured to type wheel lifting bail 131. Spring 137 biases bail 131 in clockwise direction as previously 30 set forth and, in so doing, urges the follower roller carried by arm 187 to seek engagement with the internal cam surface of cam 186. Cam 186 does not have a restricting channel, so that the follower carried by arm 187 is free to be moved 35 away from engagement with the interior of the depending flange of cam 186 when bail 131 is rocked in counterclockwise direction by cam 125. During the initial stages of the lifting of frame 139 by cam 125, cam 186 may be stationary. 40

About the time that cam 125 has rocked bail 131 to its extreme counterclockwise position, and before the drop-off of the cam is presented to its follower roller, the innermost portion of the cam surface of cam 186 is presented in engagement 45 with the follower roller carried by cam follower arm 187. During the engagement of the follower roller carried by arm 187 with whatever dwell there may be at the innermost portion of the internal cam surface of cam 186, bail 131 will be 50 held in extreme counterclockwise position and lever arm 134 will be held in a corresponding position. As cam 186 continues to rotate and the receding cam surface is presented to its follower (the recession being radially away from the axis 55 of the cam), bail 131 will be restored by a controlled motion to its extreme clockwise position, and type wheel supporting frame 139 will be restored to its lowermost position to render visible 60 the character just previously printed. It will be apparent that when the type wheel frame 139 is being elevated, the cam follower, by means of which the lowering of the frame will subsequently be controlled, is moved out of engagement with 65 its cam surface, and that when the frame 139 is being held in elevated position, and is being lowered, the cam follower by which its elevation was accomplished will be held out of engagement with the elevating cam.

Of the principal mechanisms of the typing unit 16, there remains for consideration only the function mechanism. This mechanism is, in general, similar in construction and operation to the function mechanism disclosed in the copending 75

application of Albert H. Reiber, Serial No. 77,796. The function mechanism may be understood to include those mechanisms by which such operations shift, unshift, carriage return, line feed, signal bell operation, and transmitter disablement are selected and accomplished. Those functions which are materially different from the corresponding functions, as disclosed in the copending application of Albert H. Reiber, Serial No. 77,796, and which will be described in detail, are shift and unshift, by means of which selection of characters in the letters or figures bank of type pallets is accomplished.

The selection of a function is accomplished by means of a testing mechanism which is cam controlled. Since the testing operation can be conveniently performed by a groove or channel cam, a channel 191 is provided in the upper surface of print bail operating cam 151. A cam follower, which could not be shown in Fig. 1, is fitted into the groove or channel 191 in cam 151, and the follower arm is part of a bail 192 which is operated to test for the selection of functions, and to condition in accordance with the selection one or more of a plurality of function bars, indicated generally by the reference numeral 193. The manner in which the presence of a function is tested and in which the function bars 193 are conditioned is fully disclosed in the copending application of Albert H. Reiber, Serial No. 77,796.

The function bars 193 are pivotally mounted upon rod 194. Rod 194 is supported between spaced arms 196 and 197, which comprise a function bail pivoted upon pivot rod 198. The lower arm 197 of the function bail has integral therewith an arm 199 at the free end of which is supported a cam follower roller 201. A function cam 202, carried by the main cam sleeve 130, has its periphery engaged by roller 201, and when cam 202 occupies rest position, arm 199 and the function bail comprising arms 196 and 197 are disposed in extreme clockwise position.

At their free ends, the arms 196 and 197 support a spring post 203 to which is hooked one end of each of a plurality of tension springs 204. Each of the springs 204 has its other end connected to one of the function bars 193. Thus, the function bars 193 are biased in counterclockwise direction, and movement of any of them in clockwise direction is opposed by its particular tension spring 204.

The conditioning of function bars 193, under the control of bail 192 in response to a function selection, is manifested by rotation of one or more of the function bars 193 through a small angular distance in clockwise direction. Such rotational movement brings the conditioned function bar out of alignment with the unselected function bars and into position to initiate or perform its assigned function. Immediately after the conditioning of one of the function bars 193, cam 202 rocks its follower arm 201 and the function bail comprising arms 196 and 197 in counterclockwise direction. Since the function bars 193 are pivotally mounted upon rod 194, carried by bail arms 196 and 197, they are moved endwise toward the rear of the printer as cam follower roller 201 is moved to its outermost position with respect to cam 202. Those of the function bars 193 which have not been conditioned by being rocked in clockwise direction are reciprocated idly while one conditioned function bar 193 initiates or performs the assigned function as a result of the reciprocatory movement. The rod 194, carried by function bail arms 196 and 197, also is pivotally en-

gaged by a spacing pawl 206 which is reciprocated to effect spacing of the platen carriage as the function bars 193 are reciprocated rearwardly of the printer. The spacing operation and the performance of the several functions excepting shift and unshift are sufficiently similar to those disclosed in the copending application Serial No. 77,796, that it is considered unnecessary to describe them in detail here. However, the shift and unshift functions will now be described.

The hereinbefore identified stud 142, which guides the type wheel supporting frame 139 in its upward and downward movements, extends through a horizontally extending slot in a slide member 207. The slide member 207 is also provided with an open ended slot 208 through which extends a screw 209, carried by the frame of the typing unit. The stud 142 and screw 209 support the slide member 207 and guide it throughout a limited sliding movement forwardly and rearwardly of the typing unit.

The slide member 207 has integral therewith a vertically extending arm 211. The arm 211 is provided near its upper end with a step cut aperture 212. By virtue of the step cutting, two abutments or stop surfaces are provided, the lower of which is indicated by the reference numeral 213, and the upper of which is indicated 214 and is the upper end of the aperture 212. The type wheel supporting and lifting frame 139 has adjustably secured thereto a bracket 216, which has an arm 217, extending into the aperture 212 of the slide member 207. When the type wheel lifting frame 130 is lifted by bail arm 134, operating through spring 137, arm 217 of bracket 216 may encounter either of the stop surfaces 213 or 214, depending upon whether the slide member 207 is presented in its rearmost or foremost position, and thereby the type wheel lifting frame 139 will be arrested in either of two positions of elevation while bail arm 134 continues to be rocked to its extreme counterclockwise position. When the type wheel lifting frame 139 is arrested by the lower stop surface 213 of slide member 207 the upper row of type pallets carried by type wheel 144 is presented in alignment with the operating extension 178 of print hammer 169, and when the frame 139 is permitted to be lifted until its arm 217 encounters the uppermost stop surface 214, the lower row of type pallets will be presented in alignment with the print hammer 169, and with the character impression level of the platen 129.

The movement of slide member 207 from one to the other of its two positions is accomplished by two levers pivoted upon stud 142, one of the levers being pivotally supported between slide member 207 and the frame elements which support stud 142 and which, therefore, is behind slide member 207 and cannot be seen in Fig. 1, and the other of which is pivotally supported between slide member 207 and type wheel lifting frame 139 and is indicated by the reference numeral 218 in Fig. 1. A screw 219 establishes a pivotal interconnection between the slide member 207 and its operating lever 218. Lever 218 is provided with a depending finger 221. The first and second of the function bars 193, counting from the top, each have extending laterally therefrom a lug, one of which appears in Fig. 1 and is indicated by the reference numeral 222. The depending finger 221, of lever 218, occupies a position directly in the path of lug 222 when the function bar which carries lug 222 has been conditioned for function performance by being rocked in clockwise direction preparatory to being moved endwise by cam 202, 75

operating through arm 201 and bail arms 196 and 197. When lever 218 is in its extreme counterclockwise position, which is the condition when slide member 207 occupies the rearmost of its possible positions, finger 221 is disposed substantially at the limit of movement of lug 222 so that it will not be affected if the function bar by which lug 222 is carried is conditioned and reciprocated. When, however, the slide member 207 occupies the foremost position, lever 218 will be presented in extreme clockwise position and its depending finger 221 will be positioned to be engaged by lug 222, early in the cycle of movement of that lug rearwardly of the typing unit. Under these conditions counterclockwise movement of lever 218 by lug 222, as it moves rearwardly of the typing unit, will result in rearward movement of slide member 207 which is articulated to lever 218 by screw 219, whereby slide member 207 will be shifted to its rearmost position with stop surface 213 in the path of arm 217 carried by type wheel lifting frame 139. It will be understood that the timing of the apparatus is such that type wheel supporting frame 139 is held lowered by bail arm 134 when slide member 207 is shifted so that there shall be no interference between arm 217 and the step-cut portion of aperture 212 during the movement of slide member 207.

The restoration of the slide member 207 to its forward position is accomplished by the lever which corresponds to lever 218 and which is pivoted between slide member 207 and the frame member which supports stud 142 so that it does not appear in Fig. 1. A screw 223 establishes a pivotal connection between this lever and the slide member 207. This pivotal interconnection is above stud 142 so that when the lever is rocked in counterclockwise direction, the slide member 207 will be moved forwardly of the typing unit to its foremost position. The lower end of the lever which is pivoted to slide member 207 at 223 may be similar to the lower end of lever 218 so that when it is in extreme clockwise position, it will be disposed in the path of the laterally extending projection of that one of the function bars 193, the function of which is to shift the slide member 207 to its foremost position to permit the type wheel lifting frame 139 and the type wheel 144 to be lifted to their uppermost position whereby printing may be effected from the lower row of type pallets.

It will be apparent from the foregoing description of the levers which control the shifting of slide member 207 that both of these levers effect control by being rocked in counterclockwise direction, one being operative to shift the slide member 207 rearwardly and the other being operative to shift it forwardly. It will also be apparent that as either is rocked in counterclockwise direction by its assigned function bar 193, the motion which it imparts to the slide member 207 will cause the other lever to be rocked in clockwise direction so that they will be presented alternately in position to be operated by their respective function bars.

In addition to operating the function levers 193 and the spacing pawl 206, the function bail also operates a ribbon feed lever 226. This lever is pivoted upon a stud 227 fixed to a stationary portion of the typing unit and its lower end engages the arms 196 and 197 of the function bail. At its upper end, lever 226 is articulated to a link 228 which has a slot in which is disposed one end of a ribbon feed lever 229. The ribbon feed

mechanism which is operated by lever 229 may be substantially identical with that disclosed in the copending application of Albert H. Reiber, Serial No. 77,796. The ribbon feed mechanism supporting plate 172 supports pairs of vertically disposed pins 231 which serve as guides for the inked ribbon 232, and there is also a semicircular ribbon guide which is supported by the type wheel lifting frame 139 in spaced relation to the type wheel 144 between the type wheel and the platen 149. Thus, the ribbon guide 233 is lifted each time the type wheel 144 is lifted, and a portion of the ribbon 232 is always positioned between the type wheel 144 and the platen 149 so that inked type impressions may be produced upon a page carried by platen 149.

The platen 149 is rotatably supported by the opposed ends of a carriage 236. The carriage is supported for movement transversely of the typing unit by rails, one of which is indicated as 237, secured to the rear casting member 64. The casting 64 also supports near the top thereof a bracket 238 which has a threaded aperture in coaxial relation to the platen 149. A bushing 239 threadedly engages the aperture in bracket 238 and rotatably supports a square rod 241 which enters platen 149 through one of the hubs therein and passes through a square portion of a tube which extends from end to end of the platen 149. The square shaft 241 is of sufficient length that it may extend into or through the square portion of the tube on the interior of platen 149 in any position which carriage 236 may occupy in its travel back and forth upon its supporting rails. Square shaft 241 has secured thereto a crank 242 which may be rotated manually to impart rotation to square shaft 241 and, through its co-operation with the square portion of the tube into which it extends, rotation may be imparted to platen 149.

Carriage 236 also supports a paper guiding plate or basket 243 which is disposed below the platen for guiding a page in the printing position and which, in turn, supports pressure rolls 244 and paper guide fingers 246. Carriage 236 may have associated therewith character spacing mechanism and line feeding mechanism in accordance with the disclosure of the copending application of Albert H. Reiber, Serial No. 77,796. A rotatable drum 247 is provided for housing a carriage return spring. A carriage return belt 248 has one end secured to the periphery of drum 247 and the other end secured to carriage 236.

Terminal blocks and slip connections are provided for connecting the various electrical circuit elements in the keyboard transmitter mechanism and in the typing unit to external circuits. The reference numeral 251 indicates a terminal block which is mounted on the keyboard base casting 18 behind the typing unit. Terminal block 251 has terminals 252 individually engaged by slip connection tongues 253 carried by a slip connection block 254. Slip connection block 254 is secured to the rear portion 62 of the primary typing unit casting below the secondary or carriage supporting casting 64. The contacts 252 and tongues 253 may form electrical connections between the electromagnet 68 carried by the typing unit and the transmitting contact springs 27 carried by the keyboard base and between the selector magnet and external circuit. Thus, the secondary casting and all of the elements which it supports may be removed from the typing unit without disturbing the electrical connection between the selector magnet 68 and the transmit-

ting contacts and between the external circuit and both the selector magnet and the contacts. Also the entire typing unit may be removed from the keyboard base by removal of the thumb screws 5 63 whereby the slip connection tongues 253 will be removed from engagement with contacts 252 without disturbing the electrical connections between the transmitting contacts and external circuit.

10 The general operation of the typing or receiving unit hereinbefore described is as follows: Permutation code signals impressed upon a telegraph line to which the receiving unit is connected enter the receiving unit at terminals 252 and slip 15 connection 253 and are impressed upon the selector magnet 68. Gear 78 and the shaft which it drives, being in operation, selector assembly 67 which is friction driven is released for a cycle of operation by the start impulse of a signal 20 combination in accordance with the well-known practice employed in the operation of single magnet selector mechanisms controlled by start-stop signals. As the selector cam assembly 67 rotates, the sword levers contained in the sword lever 25 mechanism 69 are set in characteristic positions according to the signal combination received. Just before the selector cam assembly 67 completes a cycle of rotation, its cam projection 120 30 engages arm 115 of bail 116 and rocks the bail in clockwise direction whereby clutch throwout lever 112 is withdrawn from restraining engagement with driven clutch element 108, carried by the front shaft, whereupon the driven element 108 is shifted into engagement with driving element 35 107, and cam sleeve 113 is set in operation for a cycle comprising one revolution.

The first operation performed after cam sleeve 113 is set in operation is the clockwise rocking of transfer bail 91, by transfer cam 119, operating 40 through cam follower roller 122 and follower arm 123. Transfer bail 91 operates to set the code discs contained in the code disc selector mechanism 84 in correspondence with the setting of the sword levers. The shifting of the code discs 45 to accomplish the selection of a new stop pin 86 is accompanied by the camming of the previously selected stop pin into unselected position whereby the restraint upon type wheel stop arm 87 is removed and shaft 84 and type wheel 144 rotate 50 to seek a new stop position. At this time, the type wheel 144 is held in its lowermost position by the type wheel lifting bail 131 and bail arm 134.

As soon as the transfer has been accomplished, 55 the selector cam barrel 67 may be released for rotation to effect the setting of the sword levers according to a new signal combination. The timing of the operation of selector cam assembly 67 and of cam sleeve 113 carried by front shaft 103 60 is such, with respect to the speed of operation of transmitting apparatus, in response to which this receiving mechanism is intended to operate, that the transfer has been effected before the selector cam barrel is released by the start impulse of the next signal combination.

A predetermined interval after the transfer operation has been performed, cam 125 begins to rock type wheel lifting bail 131 in counterclockwise direction and the type wheel 144 is 70 elevated into printing position. The position in which the type wheel will be arrested will be determined by the position occupied by slide member 207. Bail 131 will, however, be rocked to extreme clockwise position regardless of the position in which type wheel 144 is arrested, spring

137 yielding to permit the motion of bail 131 to be completed.

A short angular distance before cam 125 has rocked bail 131 to extreme counterclockwise position, cam 118, carried by cam sleeve 113, engages 5 clutch throwout lever 128 of the clutch which comprises driving element 124 and driven element 129 on the main shaft or inner cam shaft, whereby the main assembly 130 is set in operation. By the time cam 125 has rocked type wheel lifting bail 131 to extreme counterclockwise position, internal cam 186, included in the main cam assembly 130, has assumed control of its follower arm 187, which is carried by bail 131, so that type wheel lifting bail 131 is held in extreme counterclockwise position after cam 125 has come to rest 15 and has relinquished control over bail 131.

The front shaft may be rotated at the same speed as the main shaft so that in the reception of signals continuously transmitted, the cam 20 sleeve 113, carried by the front shaft 103, will have a rest period between cycles of operation equal to the rest period of selector cam assembly 67 between successive code combinations. Cam sleeve 113 may, therefore, being its next cycle of 25 rotation before the cam assembly 130, carried by the main or inner shaft, has completed much of its cycle of operation. While cam 186 is holding type wheel 144 elevated, and before cam sleeve 113 can have rotated sufficiently far in the 30 next cycle to operate the transfer bail, the print cam 151 brings its sharp drop-off into alignment with roller 152, carried by the print bail operating lever 153, whereupon spring 158 rotates lever 153 sharply in counterclockwise direction and 35 this movement is imparted to print bail 161, which drives print hammer 169 into engagement with the selected type pallet and which overtravels sufficiently to produce an impact between the selected type pallet and a message page carried by platen 149. At substantially the same time that print cam 151 permits print bail operating lever 153 to be rocked counterclockwise by its spring 158, cam groove 191, in the upper surface of cam 151, operates its associated bail 40 192, which tests for function selection as disclosed in the copending application of Albert H. Reiber, Serial No. 77,796. The effect of such testing is that a function bar 193, which corresponds to a function that may have been found 45 to be selected is rocked clockwise through a small angular distance in opposition to its biasing spring 204, to bring it into position to initiate or perform its function.

Since tension spring 166 is effective substantially instantaneously after the printing of a character to withdraw print hammer 169 to its retracted position, which operation can be performed much more rapidly by spring 166 than it could be by cam 151, operating through bail operating lever 153, the transfer of the next signal combination can be performed sooner after the print operation than it could be with positive printing and retraction of the print hammer. The sooner after the printing operation that the 65 transfer of the next signal combination may be performed, the greater is the interval of time that may be allotted for rotation of the type wheel into a new stop position corresponding to the new selection and, therefore, the slower can be 70 the speed of rotation of the type wheel shaft 83. The maintenance of minimum rotational velocities consistent with efficient operation is desirable in order to minimize inertia effects.

Internal cam 186 is required to hold type wheel 75

144 elevated only until the print operation has been performed. As cam 151 continues to rotate and restores print bail operating lever 153 to its extreme clockwise position, cam 186 permits 5 bail 131 and bail arm 134 to return to extreme clockwise position, the restoration not being abrupt nor violent but rather being controlled and gradual.

As set forth in the description of apparatus, 10 cam 202 operates function bail lever arm 199 to reciprocate the spacing pawl 206 and the function bars 193. Immediately after the printing of a character has been accomplished, the carriage 236 may be spaced to bring a blank portion of 15 the page into position to receive the next character. If instead of a character having been selected for printing a function has been selected, and the selection evidenced by the clockwise rocking of the particular function bar by 20 operation of bail 192 substantially simultaneously with the operation of print bail lever 153, the apparatus is conditioned for the performance of the function. The operation of lever 199 by cam 202 is gradual so that there is no abruptness 25 in the performance of the function. As the function bars 193 are moved rearwardly of the typing unit by operation of function lever 199, the one of the function bars 193, which has previously been rocked into effective position 30 initiates or performs the function such as shift, unshift, line feed, carriage return, and various other desirable functions as disclosed in the copending application of Albert H. Reiber, Serial No. 77,796. The operation of function bail lever 35 199 is the last operation performed by the cams on cam sleeve 124 before the cams return to rest position, at which point, clutch throwout lever 127 separates driven clutch element 129 from driving element 124.

40 From the foregoing it will be observed that during the reception of isolated or widely separated signal combinations, there occurs a train of operations for each signal combination which begins with the setting in rotation of selector cam cylinder 67 and which ends with the arrestment of main cam assembly 130. The selector cam cylinder cooperates with the selector mechanism to set up the signal combination received, trips off the cam sleeve 113 on the front shaft, and 45 comes to rest. The cams carried by sleeve 113 transfer the signal combination to the code disc selector, elevate the type wheel to printing position under the control of the shift and unshift slide member 207, trip off the main cam assembly 50 on the inner shaft, and come to rest. The cams on the main cam sleeve 130 effect the operation of print hammer 169, test for the presence of a function selection, control the lowering of the type wheel to its idle position, effect character 55 spacing and the performance of any function selected, and come to rest.

When, however, signal combinations are being received at substantially maximum frequency, as is the case when the transmitter from which the 60 signals are being received is operated by a perforated tape, or if it is a keyboard transmitter, being operated by a skillful operator, the stop time between cycles of operation of selector cam assembly 67 will be very brief. The stop time 65 between successive cycles of the front cam cylinder 113 and the main cam cylinder 130 will be correspondingly brief, but definite phase relationships between all of the cam assemblies will be maintained. Thus, all of the cam assemblies 70 may be rotating simultaneously, and no two of 75

them may be at rest at the same time. However, the operations which they control will proceed in orderly fashion exactly in accordance with the planned timing of the receiving mechanism. Any signal combination introduced at the selector magnet 68, whether relating to the printing of a character or to the performance of a function, will have become effective for the purpose for which it was introduced before the completion of the operation initiated by the selector cam assembly 67, and there will be no storage of a signal combination requiring an additional cycle of operation of the selector cam barrel for its clearing out, as is the case in some printing telegraph mechanisms, in which the transfer 10 and printing operations are not assigned to be performed by cams included in separate cam assemblies, but are performed by cams included in a single cam assembly, and in which there is insufficient time between the transfer operation 15 and the end of the cycle of the single cam assembly for the completion of rotation of the type wheel, or other conditioning of the printing element and the actual printing operation. In some printing telegraph receiving apparatus having a single operating cam assembly, such for example, as that exemplified in the copending application Serial No. 77,793, the printing operation is timed to precede the transfer operation 20 in each cycle of the cam assembly so that the 25 printing operation always lags one cam cycle behind the transfer operation, and at the completion of any message, the signal combination for the last character or function remains in storage in the code disc selector mechanism and necessitates the introduction of an idle cycle of the selector cam assembly for its clearing out. In the printing telegraph receiver mechanism according to the present invention, the printing operation and also the operation of the function 30 mechanism follows the transfer operation in the general cycle of operation of the mechanism which may be considered as beginning with the starting of the selector cam assembly 67 into rotation and terminating with the arrestment of 35 the cam assembly 130 carried by the main or inner operating shaft. It will thus be apparent that the printer always clears out and prints in accordance with the last signal combination received and no signal combination is ever left in 40 storage in the selector mechanism.

In the foregoing general description of the printing telegraph apparatus, in accordance with the invention, certain details were not described because the description was restricted to Fig. 1, 55 in which details could not be clearly shown. They are, however, shown in Figs. 3 and 4, and an alternative embodiment of one feature of the invention is shown in Figs. 2 and 3. The details and alternative embodiment will now be described having reference particularly to the detailed showings.

Modified type pallet operating mechanism

Reference numeral 261 which appears in Fig. 65 2 designates a print hammer operating bail which is in the form of a bell crank lever and comprises arms 262 and 263. The free end of arm 262 supports a cam follower roller 264 which engages the periphery of print controlling cam 266 which 70 may be identical with print controlling cam 151 in Fig. 1 and may operate in exactly the same manner and according to the same timing. The pivotal mounting for bail 261 (not shown) may be identical with pivot rod 154 of bail 153 in Fig. 75

1. The location of the pivotal mounting for bail 261 is indicated by the screw 267. Arm 263 of bail 261 is provided with an arcuate slot 268, the center of the arc of which coincides with 5 the pivotal axis of bail 261, through which extends a clamping screw 269 which threadedly engages one arm 271 of a bell crank 272. Bell crank 272 is pivoted coaxially with bail 261, the screw 267 serving as the upper pivot for the bell 10 crank. Arm 271 of bell crank 272 rests upon arm 263 of bail 261, and screw 269 clamps the two arms rigidly together, the slot 268 affording provision for angular adjustment of bell crank 272 relative to bail 261. Bell crank 272 has an 15 arm 273 disposed in a horizontal plane considerably above that in which arm 271 is located, and specifically, in the plane of the type wheel. A vertical bar 274 integral with arm 271 and 273 interconnects the two arms and completes bell 20 crank 272. Upper arm 273 of bell crank 272 is provided with a plurality of apertures 276, any one of which may receive one end of a tension spring 277, the other end of which is connected to a stationary bracket 278. Spring 277 biases bell crank 272 in a counterclockwise direction and thus urges cam follower roller 264 into engagement with the periphery of cam 266. Spring 277 furnishes the power for actuating the type 25 pallets, and by shifting the foremost end of spring 277 from one to another of the holes 276, the tension of the spring may be increased or decreased as desired.

At its free end, arm 273 of bell crank 272 carries a screw 279 which supports a spring post 35 281. A print hammer or type pallet operating member 282 is provided in its foremost end with an open ended slot 283 which fits over screw 279, the foremost end of print hammer 282 resting upon arm 273 of bell crank 272. Print hammer 282 is guided and further supported for reciprocational movement by a bracket 284 which may be similar to bracket 176 in Fig. 1. A tension spring 285, which has one end engaging print hammer 282 and the other end engaging spring post 281, urges print hammer 282 to extreme position of retraction, which may be determined by engagement of the closed end of slot 283 with slot 279 or by engagement of a laterally extending projection 287 of print hammer 282 with 40 adjustable eccentric 288 secured by screw 289 to stationary bracket 291 which supports ribbon spools 292. Print hammer 282 is provided with a shoulder 293 which may come into engagement with bushing 288, when the print hammer is 45 reciprocated rearwardly of the printing telegraph receiving unit, to limit the operating stroke of the print hammer and prevent excessive reciprocation of the type pallets.

In Fig. 2 the printing mechanism is shown in 50 the condition which exists just before a printing operation, bail 261 and bell cranks 262 being in extreme clockwise position and the free end of print hammer 282 being retracted well back from the type pallet. As cam follower roller 264 traverses the drop-off in cam 266, bail 261 and bell crank 272 are rocked by spring 277 to extreme counterclockwise position, the movement to this position being relatively sharp. Screw 279 engages the inner or closed end of slot 55 283 in print hammer 282 and positively reciprocates the print hammer toward the inner end of the type pallet which is aligned therewith. The positive movement of print hammer 282 by bell crank 272 ceases when cam follower roller 70 264 engages the innermost portion of the per-

iphery of cam 266 and the termination of the positive movement occurs just before the free end of print hammer 282 engages the aligned type pallet. The kinetic energy of print hammer 282 causes the print hammer to continue to move 5 rearwardly of the printing unit after bell crank 272 has been arrested, the inner end of slot 283 drawing away from screw 279 and spring 286 yielding to permit the additional or overtravel movement of the print hammer. The overtravel 10 is sufficient to drive the type pallet radially of the type wheel to effect printing, the free end of the print hammer 282 moving into the space between the type pallet on either side of the one actuated. As soon as the kinetic energy of print 15 hammer 282 has been dissipated, spring 286 retracted the print hammer until the inner end of slot 283 engages screw 279 or until projection 287 engages bushing 288, and such retraction is sufficient to withdraw the free end of the print 20 hammer from between the type pallet even though the rotation of cam 266 may not have been sufficient to begin the movement of bail 261 and bell crank 272 in clockwise direction. From the foregoing, it will be observed that printing 25 is accomplished by overtravel of the print hammer as in the embodiment of the invention previously described. In the mechanism according to Fig. 2, however, only the print hammer 282 overtravels whereas in the embodiment shown 30 in Fig. 1, the print hammer and the bell crank to which it is articulated overtravel.

Modified type wheel structure

Fig. 3 discloses a type wheel for the hereinbefore described printing telegraph receiving unit which may be considered as an improvement on the type wheel disclosed and claimed in copending application Serial No. 77,794 filed May 4, 1936 by Howard L. Krum et al. The type wheel 35 is indicated generally by the reference numeral 301 and its foundation is a cast or turned wheel which may comprise upper and lower flanges 302 and 303, respectively, joined by integral drum portion 304. The inner surface of drum portion 40 304 is cylindrical and the external surface includes a ridge 306 integral with the drum portion 304 and located midway between flanges 302 and 303. The face of ridge 306 may be flat and the sides thereof are curved toward the flanges 45 302 and 303, the inner faces of which also curve to meet the curving sides of ridge 306 and form therewith spaced annular grooves of semicircular cross section. A plurality of radially directed type pallet slots are provided in the type wheel 50 301, the slots being cut entirely through the flange 303, entirely through the drum portion 304, but only partially through the thickness of flange 302.

Each of the slots in type wheel 301 receives and 55 slidably supports the shanks 307 of two type pallets 308. The type pallet shanks 307 extend into the interior of type wheel 301 sufficiently far that they may be engaged and actuated by print hammer 282 to effect printing. The type pallets 60 308 in the upper row have in their shanks 307 notches 309 which open downwardly and those in the lower row have similar notches 309 which open upwardly. A garter spring 311 extends through all of the notches 309 of the type pallets 65 308 in a row and biases them to their innermost positions radially of the type wheel. The annular ridge 306, which in cooperation with the inner faces of the flanges 302 and 303 defines peripheral grooves, separates the garter springs 70 308 in a row and biases them to their innermost positions radially of the type wheel. The annular ridge 306, which in cooperation with the inner faces of the flanges 302 and 303 defines peripheral grooves, separates the garter springs 75

311 and maintains them in the desired positions. When any type pallet 308 is reciprocated outwardly radially of type wheel 301 by print hammer 282, the garter spring 311 which engages the shank of the type pallet distends slightly, thus permitting the movement of the type pallet, and thereafter restores the type pallet to innermost position.

The widths of the shanks of type pallets 308 are such that the lower of the shanks 307 of the lower row are substantially flush with the lower surface of flanges 303 and the type pallets are retained in the slots in type wheel 301 by a plate 312 which may be secured to flange 303 by a plurality of screws 313 threadedly engaging sectors of flange 303 between slots therein. Plate 312 may have a depressed central portion 314 which carries a locating pin 316 and has a plurality of apertures for clamping screws. A hub 317 slidable upon type wheel shaft 88 supports the depressed portion 314 of plate 312 and is provided with a slot 318 which receives locating pin 316 and thereby establishes a predetermined angular position between type wheel 301 and hub 317. Clamping screws 319 extend through the apertures in the depressed portion of plate 312 and threadedly engage hub 317 thereby clamping type wheel 301 securely to the hub.

Keyboard transmitter shunt unlatching mechanism

If reference is had to copending application Serial No. 77,796 of Albert H. Reiber, description will be found therein of apparatus for performing a function which involves the closure of a pair of contacts and the opening of another pair of contacts. The contact pair which becomes closed places a direct shunt across the keyboard transmitter contacts, so that impulses cannot be impressed upon the line if the local keyboard transmitter mechanism is operated. The other pair of contacts is included in the circuit of the start magnet of a tape transmitter if such a transmitter is to be used, so that when the contact pair is opened the start magnet of the tape transmitter will be de-energized and the transmitter will be arrested. The copending application discloses a latch for latching in operated condition the function lever which closes the first described pair of contacts and opens the other pair of contacts. The copending application also discloses a manually operable control located at a point remote from the keyboard for unlatching the function lever. The present invention includes apparatus for unlatching the transmitting contact shunt function lever directly from the keyboard, and by means of a key lever which is normally operable for initiating the transmission of a signal combination.

Referring now to Figs. 2 and 4 the reference numeral 321 designates contact springs which may be connected by suitable conductors so that when closed as shown in Fig. 2 they shall establish a direct shunt or a short circuit across the keyboard transmitting contacts previously described. Reference numeral 322 indicates one of a pair of normally closed contact springs which may be included in the circuit of a tape transmitter mechanism and which, when opened as shown in Fig. 4, which is intended to correspond in condition to Fig. 2, the circuit of the start magnet will be interrupted and the magnet will become de-energized to effect arrestment of the tape transmitter. The circuits form no part of the present invention and they are

fully shown in copending application Serial No. 77,796.

A function lever 323 pivoted at 324 is biased in clockwise direction by a tension spring 326 and normally occupies the dotted line position shown in Fig. 2. Lever 323 is provided with contact operating extensions 327 and 328, the former of which closes contact pair 321, and the latter of which opens contact pair 322 when lever 323 is rocked to extreme counterclockwise position which position is indicated in full line in Fig. 2. The rocking of lever 323 to extreme counterclockwise position is accomplished by one of the previously identified function bars 193. Function lever 323 is provided with a latching lug 329 which, when the particular function bar 193 has been rocked in clockwise direction during the hereinbefore described operation of testing for functions, falls in against the left-hand side of the function bar 193 and holds it from returning to extreme counterclockwise position at the end of the function testing operation. Thereafter upon the rearward reciprocation of function bars 193, the particular one shown in Fig. 2 which has become latched by projection 25 329, rocks lever 323 to the position shown in full lines, thus effecting the closure of contact springs 321 and the separation of contact 322.

A bracket 331 secured to secondary casting 30 member 64 pivotally supports a latch lever 332 which is biased in counterclockwise direction by tension spring 333. At right-hand end as viewed in Fig. 4, lever 332 is step-cut to provide a shoulder for engaging lever 323 near its right-hand end, as viewed in Fig. 2, and blocking the return of lever 323 to normal or extreme clockwise position. When lever 323 occupies the normal or dotted line position as shown in Fig. 2, the latching shoulder of lever 332 underlies a portion of lever 323.

At its left-hand end as viewed in Fig. 4 the lever 332 has a portion 334 sloping obliquely downwardly. In the initial portion of the description of Fig. 1, the key levers of the keyboard transmitter mechanism were indicated generally by the reference numeral 21. A particular key lever which initiates the generation of a signal combination that will be hereinafter specifically identified is indicated in Fig. 4 by reference numeral 336. Key lever 336 has secured thereto adjacent to the point at which it is pivotally mounted, a clamp 337 which includes reverted fingers 338 fitted over one edge of the key lever, and clamping screw 339 engaging the other edge of the key lever and drawing reverted fingers 338 firmly into engagement with the first mentioned edge. Clamp 337 has secured therewith, an arm 341 which extends rearwardly of the keyboard transmitter mechanism (rightwardly as viewed in Fig. 4) and arm 341 has a vertically directed portion 342 which emerges from keyboard base casting 18 through an aperture at the rear thereof and terminates just under lever 332 adjacent to the downwardly sloping portion 334 thereof.

In the normal condition of the transmitter shunt function mechanism, function lever 323 is in extreme clockwise position and latching lever 332 is also in extreme clockwise position with its latching shoulder underlying function lever 323 by which lever 332 is held in extreme clockwise position in opposition to tension spring 333. When lever 332 is in this position, its left-hand end as viewed in Fig. 4 is held elevated above 75

the upper end of arm 342 of clamp 337 a sufficient distance that arm 342 will not come into engagement with any portion of lever 332 upon being rocked in counterclockwise direction by the depression of key lever 336. Thus, latching lever 332 places no drag upon key lever 336 when function lever 323 is in unlatched condition and the "touch" of key lever 336 is entirely normal.

When the printing telegraph receiving unit responds to the signal combination which is assigned to the operation of function lever 323, the lever is rocked in counterclockwise direction and in being so rocked, it clears the latching shoulder of lever 332 whereupon spring 333 rocks lever 332 in counterclockwise direction to interpose the latching shoulder into the restorational path of lever 323 and the left-hand end of lever 332 as viewed in Fig. 4 rocks downwardly into a position of substantial engagement with the upper end of arm 342 of clamp 337, as shown in Fig. 4.

When it is desired to unlatch function lever 323, key lever 336 is depressed. This causes arm 342 of clamp 337 to be rocked in counterclockwise direction whereby downwardly sloping portion 334 of lever 332 is cammed upwardly. Lever 332 is thus rocked in clockwise direction sufficiently to disengage the shoulder at the right-hand end thereof from function lever 323, which is restored to extreme clockwise position against fixed stop 343 by tension spring 326, thereby moving into position to overlie the right-hand end of lever 332 and hold it depressed, whereby the left-hand end, which has the downwardly sloping portion, is held elevated.

Although the clamp 337 may be secured to any of the key levers 21, it has been found particularly satisfactory to secure it to the key lever which initiates the generation of the unshift or letters signal combination, identified herein as 336. According to a widely used system of printing telegraph signal transmission, each signal combination representing a character or a function consists of a permutation code combination of marking and spacing impulses preceded by a start impulse and followed by a stop impulse. It is frequently the custom to represent a marking impulse by a closed line condition, in which case current flows, and a spacing impulse by an open line condition in which case no current flows. It is also the custom to employ a spacing condition for the start impulse and a marking condition for the stop impulse. In the rest condition of the transmitting apparatus, a pair of contacts that are identified with the stop impulse are closed and remain closed. When the transmitter is set in operation, these contacts are opened, thereby creating a spacing condition of the line which is the start impulse. The impulses for the particular signal combination are then generated successively, and after the last code impulse has been generated, the stop impulse contacts are permitted to be closed whereby the stop impulse is impressed upon the line. The start impulse of spacing nature sets in operation the receiving selector mechanism of a printing telegraph receiving unit connected to the line and the stop impulse of marking nature arrests the receiving selector mechanism. It is also customary to permit successive marking impulses to overlap, so that two or more successive marking impulses establish on the line a single prolonged period of marking condition.

It will be apparent that when contact springs 321 are closed and function lever 323 is latched,

a closed line condition duplicating the rest condition of the stop impulse contacts will be connected in shunt across the stop impulse contacts so that even if the transmitting distributor should be released for operation no start impulse of spacing nature will be applied to the line due to the opening of the stop impulse contacts. When key lever 336 is operated, it will release the transmitting distributor sleeve 37 for a cycle of operation. Arm 342 may be arranged to be moderately slow in tripping latch 332 so that the transmitting cam assembly shall have rotated beyond the angle during which the start impulse is generated and shall be attempting to impress upon the line the code impulses. Until the contact springs 321 shall have become separated, these code impulses will not actually be applied to the line, but after the separation of the contact springs the line will be under the control of the transmitting distributor cam assembly. According to a previously mentioned commonly used permutation code system of printing telegraph signal transmission, the all marking combination is assigned to the unshift or letters function. In this signal combination the spacing condition of the start impulse is followed by a succession of marking impulses which overlap and the last of which overlaps the beginning of the stop impulse so that the line is continuously closed following the start impulse. Arm 342 of clamp 337 carried by key lever 336 may be permitted to trip off latch lever 332 at any time during the transmission of the code impulses of the letters or unshift signal and the line will not be thereby affected, because the line will continue to be closed following the opening of contact springs 321 throughout the transmission of the remainder of the code impulses and including the stop impulse. The receiving mechanism of any printing telegraph unit connected to the line will thus be maintained in rest or stop condition and there will be no manifestation of the opening of contact springs 321 nor of the rotation of the transmitting distributor in response to operation of the letters key lever 336.

Should the tripping of latch 332 be assigned to any other key lever than the letters key lever, the signal combination generated by operation of that key lever will include at least one spacing impulse. Such impulse may result in the transmission of a jumbled signal combination for the reason that if latch 332 is tripped off so as to permit opening of contact springs 321 after the start impulse interval of the transmitting distributor cycle but before the generation of the spacing impulse in the code combination the receiving selector mechanisms of printing telegraph receiving units connected to the line will be set in operation in response to the spacing impulse in the code combination and not in response to the start impulse preceding the code combination, and will operate after the transmitting distributor has come to rest thus interpreting the stop impulse as one or more marking impulses of a code combination. The result will be the printing of an undesired character or the performance of an undesired function. It will be observed from the foregoing that the letters or unshift key lever is particularly well adapted to the release of latch 332.

Although specific embodiments of the features of invention have been disclosed and described herein, it will be understood that the invention is not limited to such specific embodiments but is capable of modification, reorganization, re-

arrangement, and substitution of parts and elements without departing from the spirit of the invention and within the scope of the appended claims.

5. What is claimed is:

1. In a printing telegraph apparatus, a keyboard transmitter mechanism including a plurality of key levers, a receiving apparatus including a function lever, means for actuating said function lever, means for latching said function lever in actuated condition, and means associated with one of said key levers for releasing said latching mechanism.

10. 2. In a printing telegraph apparatus, a keyboard transmitter mechanism including a plurality of key levers, a receiving apparatus including a function lever, means for actuating said function lever, means for latching said function lever in actuated condition, and means engageable by one of said key levers only when said function lever is in latched condition for releasing said latching means.

15. 3. In a printing telegraph apparatus, a keyboard transmitter mechanism including a plurality of key levers and a plurality of transmitting contacts controlled by said key levers, a receiving apparatus including a function lever, means for actuating said function lever, means operated by said function lever for short circuiting said transmitting contacts, means for latching said function lever in actuated condition, and means associated with a predetermined one of said key levers which controls the transmitting contacts to generate a signal combination the code impulses of which maintain a line condition identical with that afforded by the contact short-circuiting means for releasing said latching means.

20. 4. In a printing telegraph apparatus, a keyboard transmitter mechanism including a plurality of key levers and a plurality of transmitting contacts controlled by said key levers, a receiving apparatus including a function lever, means for actuating said function lever, means controlled by said function lever for short circuiting said transmitting contacts, means for latching said function lever in actuated condition, and means carried by a predetermined one of said key levers which controls the transmitting contacts to generate a signal combination none of the code impulses of which will set in operation said receiving apparatus for disabling said latching means.

25. 5. In a printing telegraph apparatus, a telegraph line, a keyboard transmitter mechanism connected to said line including a plurality of key levers and a plurality of transmitting contacts operable under the control of said key levers to

apply to said line marking or spacing signal conditions, a receiving apparatus including a function lever, means for actuating said function lever, means controlled by said function lever for establishing a marking signal condition which 5 blankets and renders ineffective said transmitting contacts, means for latching said function lever in actuated condition, and means associated with a predetermined one of said key levers which controls the operation of the transmitting contacts 10 to apply to said line a signal combination all of the code impulses of which are of marking signal nature for disabling said latching means.

6. In a printing telegraph apparatus, a signal transmitting mechanism, a plurality of key levers 15 for individually controlling said signal transmitting mechanism, a receiving apparatus, and a mechanical device in said receiving apparatus operable thereby into engagement with one of said key levers and restorable by said one key 20 lever to unoperated condition out of engagement with said one key lever.

7. In a printing telegraph apparatus, a signal transmitting mechanism, a plurality of key levers for individually controlling said signal transmitting mechanism, a signal receiving apparatus, a mechanical device in said receiving apparatus operable thereby, and latching means for said mechanical device movable into engagement with one of said key levers and restorable by said one key 30 lever to unlatching condition out of engagement with said one key lever.

8. In a printing telegraph apparatus, a signal transmitting mechanism, a plurality of key levers for individually controlling said signal transmitting mechanism, a signal receiving apparatus, a mechanical device in said receiving apparatus operable thereby, and latching means for said mechanical device normally out of engagement with any key lever and movable into engagement with 40 one of said key levers upon latching said mechanical device and restorable by said one key lever to unlatching condition out of engagement with said one key lever.

9. In a printing telegraph apparatus, a signal 45 transmitting mechanism, a plurality of key levers for individually controlling said signal transmitting mechanism, a signal receiving apparatus, a mechanical device in said receiving apparatus operable thereby, means for latching said mechanical device in operated condition, and means carried by one of said key levers into engagement with which said latching means moves upon latching said mechanical device for disabling said 50 latching means.

55. CARL A. LEVIN.
